UNITED STATES PATENT OFFICE

EDWARD C. SASSER, OF CHEVY CHASE, MARYLAND

SMOKER'S PIPE

Application filed June 17, 1931. Serial No. 545,088.

My invention relates to new and useful improvements in smokers' pipes, and has for an object to provide a pipe wherein the smoke, in passing through the stem of the pipe, will travel in a tortuous passageway to thus prevent the hot smoke from too quickly reaching the smoker's tongue.

Another object of the invention is to so arrange the pipe that instead of there being a forced draft when the pipe is used there is substantially a vacuum formed, which will cause the pipe to burn more evenly than would otherwise be the case.

Still another object of the invention is to provide a pipe wherein the smoke is drawn from the bowl rearward around a tube situated in the stem and then forwardly again towards the bowl and finally rearwardly into the smoker's mouth, thus, in reality, multiplying the length of the stem, so that the smoke will have a chance to cool before reaching the smoker's mouth.

Still another object of the invention is to provide a pipe wherein when smoked, the air being withdrawn from the tube and stems substantially creates a vacuum in the bowl of the pipe rather than a forced draft, thus causing all of the parts of the tobacco to burn slowly and evenly.

A still further object of the invention is to provide an arrangement which may be quickly fitted in most pipes or may be a part of a newly constructed pipe.

With these and other objects in view, the invention consists in certain new and novel arrangements and combination of parts, as will be hereinafter more fully described and pointed out in the claims.

Referring now to the drawing showing a preferred embodiment,

Fig. 1 is a sectional view of the pipe showing the arrangement of the tube and stems;

Fig. 2 is a sectional view taken on the line 2-2 of Fig. 1;

Fig. 3 is a fragmentary section of the tube with a portion broken away for the sake of clearness;

Fig. 4 is a view of the mouthpiece with the inner stem;

Fig. 5 is a view similar to that of Fig. 3

but showing a slightly modified form of tube. Referring now more particularly to the drawing, there is shown the pipe 1 comprising the usual bowl 2, stem 3, and the mouthpiece 4, which may be of hard rubber, bakelite, or any other suitable material. It will be seen that this mouthpiece is slightly reduced, as at 5, and although it is shown as slipped into a stem 3 it might be internally screw-threaded, if desired.

Fitting within the mouthpiece 4 is the central or inner stem 6, which may be made of aluminum, and is split or bifurcated at its end, as at 7. Fitting over this inner stem is what I term the tube 8, which is slightly larger in diameter than the stem 6, this tube 8 extending from the reduced portion of the mouthpiece all the way through the pipe stem 3, through the bowl, and may rest on the far side thereof. This tube 8, as shown in Fig. 3, has the closed end 9 but is perforate, as at 10, while the rear end is slightly flared, as at 8', to thus center it with respect to the internal bore of the stem 2. The split end or prongs 7 of the inner stem 6 are bent slightly outwardly, as may be seen in the several views, so that when the mouthpiece and the stem 6 are pulled outwardly, the prongs will tend to ream or clear out this tube 8.

When the tobacco (not shown) is placed within the bowl 2 and the smoker draws on the pipe, it will be seen that the air will be withdrawn from the stem 6 and also from the tube 8, but as the tube 8 is perforate, as at 10, the air will also be removed from around the tube and from the bowl 2 of the pipe, it being remembered that the tube 8 is less in diameter than the bore of the stem 3 of the pipe. Thus, it will be seen that when the pipe is smoked, there is substantially a vacuum formed in the bowl of the pipe and in the tube and stem, which means a slow and complete burning of the tobacco rather than a forced draft, which might draw it just centrally of the bowl.

The smoke, in traveling from the bowl around the tube 8 to the point of the perforations 10, then forwardly of this tube, and then rearwardly again through the inner

stem 6, has a chance to cool and, in effect, is the same as a stem of substantially three times the length of the pipe stem 3. Thus, the smoke has a relatively long time to cool.

Referring to Fig. 5 for the moment, there is shown a tube 11 similar to the tube 8 in all respects, with the exception that the outer end 12 is left open, but this tube 11, when placed in position, is supposed to jam up tightly against the far edge of the bowl to thus tightly seal this tube with respect to the bowl, as should this tube not be sealed at its outer end with the pipe, the pipe will not work the way it is supposed to.

To quickly clean the pipe, it is only necessary to pull out the mouthpiece, which will also remove the tube 8, and then the tube 8 may be held in the one hand and the little mouthpiece and its stem withdrawn from the tube. The bent prongs acting as a reamer will clean out any of the tobacco tars or moisture or shreds of tobacco, which may have gotten into this tube. The outer surface of the tube may then be wiped off with a piece of paper, as well as the stem 6, and the pipe then quickly and readily cleaned.

I have found by actual service that the pipe is one which provides a very cool smoke, may be kept very clean, and provides a slow and even burning of the tobacco, which is supposed to provide the real aroma of the tobacco.

It will be understood that the mouthpiece may be made of any desirable material and, in the same way, the little tube and stem may be made of any desirable material without in any way affecting the spirit and scope of the invention.

Having thus described my invention, what I claim as new and desire to secure by Letters Patent is:—

1. A tobacco pipe comprising a bowl and a stem, a mouthpiece fitting within the stem, an inner stem fitting within the mouthpiece, a tube fitting over the stem and of slightly larger diameter than the said stem, said tube extending across the bottom of the bowl the tube being perforate near its rear end and the said tube being less in diameter than the bore of the stem of the pipe to thereby cause the smoke to be drawn from the bowl through a tortuous passageway before reaching the mouth of the smoker.

2. A tobacco pipe including a bowl and a stem, a mouthpiece, an internal stem within the mouthpiece fitting within the stem of the pipe and up in the bowl, a tube of larger diameter than the internal stem fitting over said internal stem and about the mouthpiece and extending clear across the bottom of the bowl, the said tube being closed at its outer end and perforate at points on its periphery near the rear end, the diameter of the said tube being less than the bore of the stem of the pipe whereby the smoke will be drawn

from the bowl around said tube and between said tube and said inner stem and then into said stem before reaching the mouth of the smoker.

3. A tobacco pipe including a bowl and a stem, a mouthpiece, an internal hollow stem having its outer end split to form outwardly extending prongs, a tube of greater bore than said internal stem fitting over said internal stem, said tube being closed at its outer end and perforate on its sides, the said tube being of less diameter than the bore of the stem of the pipe whereby the smoke will pass rearwardly, forwardly, and again rearwardly before reaching the mouth of the smoker.

4. A mouthpiece for a tobacco pipe including a hollow stem having its forward ends split and slightly pressed apart, a tube of slightly greater diameter than said stem fitting over said stem, the outer ends of said stem bearing against the inner walls of the tube, the rear end of the tube being closed but the walls of the tube near its rear end being perforate.

5. A smoker's pipe including a bowl and a stem, a mouthpiece having an internal hollow stem therein, a tube fitting loosely over said stem, said tube having holes in its walls near the rear end thereof, the outer end of the tube being open and the length of the tube being such that when fitting within the stem of the pipe the outer end of the tube is sealed with respect to the bowl and extends across the bottom of the bowl and contacts with the far side of the bowl.

In testimony whereof I affix my signature.

EDWARD C. SASSER.
